UNITED STATES PATENT OFFICE.

PETER KLITSCH, OF LOST CREEK, PENNSYLVANIA.

FLEXIBLE SHAKER-ARM.

1,182,491.

Specification of Letters Patent.

Patented May 9, 1916.

Application filed November 20, 1914. Serial No. 873,164.

To all whom it may concern:

Be it known that I, PETER KLITSCH, a citizen of the United States, residing at Lost Creek, in the county of Schuylkill and State of Pennsylvania, have invented certain new and useful Improvements in Flexible Shaker-Arms, of which the following is a specification.

My invention relates to flexible shaker arms for use in coal separators, threshing machines, and all devices wherein a reciprocating motion is imparted to a certain device through the medium of an eccentric mounted on a rotary shaft.

15 The object of my invention is to provide a flexible arm for coal shakers comprising two curved arms secured to a resilient rigid shaft at each end, and with an open space between their central portions.

20 Furthermore, the object of my invention is to provide a flexible shaft having curved arms arranged with the convex sides projecting toward each other, but not touching, leaving an open space within the same, 25 and connected at each end to rigid shafts by means of bolts extending through the curved arm and rigid portion of the shaft.

Finally, the object of my invention is to provide a flexible shaft connected to rigid 30 end pieces by means of bolts inserted through the flexible shaft and end pieces, and an iron cross piece, approximately rectangular in shape, inserted between the inner end surface of the flexible portion of 35 the shaft and the rigid piece to strengthen the tapering ends of the rigid piece caused by the apertures made therein and through which the clamping bolts extend.

With the foregoing and other objects in 40 view, my invention consists in the details of construction and in the arrangement and combination of parts as hereinafter more fully described and particularly pointed out in the claim.

45 In describing my invention in detail, reference will be had to the accompanying drawing, forming a part of this specification, wherein like characters denote corresponding parts in the several views, 50 and in which: Figure 1 is a side view. Fig. 2 is a top plan view. Fig. 3 is a perspective view of one of the iron cross pieces.

In the drawings, 1 indicates a rotary shaft upon which an eccentric, 2, is secured 55 by any suitable means. Secured upon the eccentric is an eccentric strap, 3, which ter-

minates in a solid projection, 4, having shoulders, 5 and 6, formed integrally therewith. The construction of the end piece, 4, of the eccentric strap is the same on both sides. A rigid shaft end connecting piece, 7, is secured to the eccentric strap projection, 4, clamping bolts, 8, extending therethrough in the usual manner. The construction of the eccentric and the attaching 60 of the rigid end piece thereto is the usual form of construction for which I do not claim any invention.

65 I provide two resilient connecting pieces, 9 and 10, which are provided at each end with apertures located in a staggered relation to each other in order that the connecting pieces may not be weakened, which would necessarily be the result if the apertures were formed in straight lines. The inner surface of each of the connecting pieces, 9 and 10, I provide with angular shaped grooves, 11, extending entirely across the width of the connecting strap, upon their inner end surface, and a similar groove is 70 formed in the outer surface of the rigid piece, 7, and also in the portion of the shaft, 12', which is connected at its opposite end to a shaker not shown in the drawing. The connecting pieces, 9 and 10, are connected at 75 each end to the rigid portions, 7 and 12', of the shaft, with their convex surfaces adjacent to each other in the central portion but not close enough so that their surfaces may contact. The clamp bolts, 12 and 13, are 80 inserted at each end through the apertures in the connecting pieces, and the rigid portions of the shaft, 7 and 12'. Between the under end surfaces of the rigid pieces and the resilient connections I insert pieces of 85 iron, 14, approximately rectangular in shape, which are adapted to seat in the grooves, 11, formed in the inner surface of the resilient connections and rigid portions of the shaft, and extend transversely the full width 90 thereof. The inserting of the iron cross pieces, 14, strengthens the shaft and distributes more evenly the pull of the flexible connections upon the ends of the rigid portions of the shaft.

100 The curved adjustment of the two separate pieces connecting the two rigid portions of the shaker arm allows sufficient flexibility to overcome any lost motion and the tendency of the eccentric strap to jar, thus 105 causing a loosening of the bolts at the eccentric and shaker ends of the arms; and

also to prevent the snapping off of the arm, which often happens when the shaker arm is composed of one solid piece.

The construction and operation, and advantages, of my improved flexible shaker arm, it is thought, can be fully understood from the foregoing description of the combination and arrangement of the several parts, and it is noted that slight details in the construction and proportion of the several parts may be made without departing from the scope of my invention.

Having fully described my invention, what I claim as new and desire to secure by 15 Letters Patent is:

In a flexible shaker arm, rigid end pieces provided with angular shaped grooves, curved connecting pieces provided with

transverse angular grooves adapted to register with the angular grooves in the rigid 20 end pieces, said connecting pieces having their convex surfaces adjacent to each other in the central portion thereof, means for securing said connecting pieces to said rigid pieces, and a series of rectangular pins 25 adapted to be inserted in the apertures formed by the registering of the transverse angular grooves in the end pieces and connecting pieces, substantially as described.

In testimony whereof I affix my signature 30 in presence of two witnesses.

PETER KLITSCH
